UNITED STATES PATENT OFFICE.

REUBEN M. ROSE, OF BROOKLYN, NEW YORK.

INDICATOR FOR FARE-REGISTERS.

SPECIFICATION forming part of Letters Patent No. 245,221, dated August 2, 1881.

Application filed April 14, 1881. (No model.)

To all whom it may concern:

Be it known that I, REUBEN M. ROSE, of the city of Brooklyn, in the county of Kings and State of New York, have invented certain new and useful Improvements in Passenger and Fare Indicators, of which the following is a specification.

My invention relates particularly to fare or passenger indicators for use in street-cars and other vehicles, and in which an index finger or hand is advanced by a step-by-step movement over a visible dial; but the invention might be applied to similar indicators for theaters and other public places.

The indicators for street-cars are so constructed that their index fingers or hands may be turned to a zero or fixed starting point at the beginning of each trip, and it is obvious that if not turned back to the proper point opportunity is afforded for cheating by the conductor. For example, if the index hand or finger were turned ahead to indicate 95 upon a dial divided into a hundred parts, it is obvious that the conductor might receive and ring up fifteen fares, and still have the index finger or hand indicate only 10 upon the dial.

The principal object of my invention is to provide a tell-tale which is necessarily moved in turning the index finger or hand to a zero-point, and is then left stationary, and has its backward movement prevented, while the index finger or hand is moved away from it, thus indicating the actual starting-point, and disclosing the fact if the finger or hand has not been started at the proper point.

The invention consists in the combination, with a dial and an index finger or hand and a tell-tale finger or hand, one provided with a projection engaging with the other, of a toothed circular rim surrounding the dial and a pawl carried by or formed upon said tell-tale finger or hand for engaging with said rim and preventing backward movement of said tell-tale finger or hand.

In the accompanying drawings, Figure 1 represents a face view of an indicator embodying my invention, a portion of the dial being broken away, and Fig. 2 represents a vertical section thereof upon the dotted line xx , Fig. 1.

Similar letters of reference designate corresponding parts in both figures.

A designates the case of the indicator, and B designates a dial at the front thereof, and visible through the glass face a of the case.

C designates a central shaft or axis extending from front to back of the case, and supported in proper bearings b , as seen clearly in Fig. 2.

Upon the shaft C, in front of the dial B, is an index finger or hand, B', which is fitted thereon tightly enough to cause it to turn therewith, but not so tightly that it may not be otherwise moved when the shaft is stationary.

D designates a ratchet-wheel fixed upon the shaft C, and E designates a lever which is bifurcated, so as to embrace said wheel, and is loosely fulcrumed upon the said shaft, and carries an actuating-pawl, c , which takes into the teeth of the ratchet-wheel D. At the outer end of the lever E a pull-piece may be connected. At each operation the lever is returned by a spring, d , and it will be clearly understood that by operating it the index finger or hand B' is advanced by a step-by-step movement in the usual manner.

It is obvious that the lever E might be otherwise constructed than with a pawl to cause it to engage with the wheel D, the latter in such case not being a ratchet-wheel.

With the ratchet-wheel D, I may employ a stop-pawl, to prevent its backward movement, and the indicator might have a bell operated in any suitable manner; but such devices are well known in indicators of this class, and therefore need no particular description.

Upon the shaft C, also, outside the dial B and the index finger or hand B', is a loosely-fitting tell-tale finger or hand, F, which remains stationary while the shaft turns, and is provided with a hand-piece, e , extending through the glass, whereby it may be turned. The dial B is surrounded by a toothed rim, f , which, while it permits the tell-tale finger F to be moved freely in the direction of the arrow, Fig. 1, prevents it from being moved in the opposite direction. The finger F is formed to engage with the rim f like a pawl, or carries a pawl.

As before stated, the index finger or hand B' is fitted tightly enough upon the shaft C to turn therewith, but loosely enough so that it may be turned independently thereof.

Upon the index finger or hand B' is a projection, *g*, which extends forward sufficiently far to engage with or project on the right side of the tell-tale finger or hand F.

5 Suppose, now, that during one trip the index finger or hand B' has been advanced to the position shown in dotted outline, and it is desired to turn the said finger or hand to zero or a fixed starting-point. The tell-tale finger or hand is turned by the hand-piece *e*, and, acting upon the projection *g*, turns also the index finger or hand until they both stand at the position shown in full outline in Fig. 1. If the shaft C now be turned step by step the index finger or hand will travel away from the tell-tale finger or hand, and the latter will truly indicate the actual starting-point, and disclose the fact if it was not the proper starting-point or zero. By this means it will be seen that 20 the conductor would be prevented from using 90 or any point behind zero for the starting-point without the fact being disclosed and the proper number of fares required of him.

Instead of the index finger or hand having 25 a projection extending on the right side of the tell-tale finger, a projection on the latter extending on the left side of the index finger or hand would effect a like result.

What I claim as my invention, and desire 30 to secure by Letters Patent, is—

1. In an indicator, the combination, with a dial and an index finger or hand and a tell-tale finger or hand, one provided with a projection engaging with the other, of a toothed circular rim and a pawl carried by or formed upon said tell-tale finger or hand for engaging with said rim, and preventing the backward movement of said tell-tale finger or hand, substantially as and for the purpose specified.

2. In a passenger or fare indicator, the combination, with a dial, an index finger or hand, and mechanism adapted to be operated from outside the case of the instrument for advancing said finger or hand step by step, of a tell-tale finger or hand, and a projection on one 45 finger or hand engaging with the other finger or hand, substantially as and for the purpose specified.

3. The combination of the shaft C, the dial B, the index finger or hand B', the tell-tale 50 finger or hand F, constructed to form a pawl, and the circular toothed rim *f*, all substantially as specified.

REUBEN M. ROSE.
